UNITED STATES PATENT OFFICE.

KEY D. CAMP, OF MILWAUKEE, WISCONSIN, ASSIGNOR TO A. J. LINDEMANN & HOVERSON CO., OF MILWAUKEE, WISCONSIN.

IGNITER.

1,163,241.

Specification of Letters Patent.

Patented July 7, 1914.

Application filed April 21, 1914. Serial No. 833,390.

To all whom it may concern:

Be it known that I, KEY D. CAMP, a citizen of the United States, and resident of Milwaukee, in the county of Milwaukee and State of Wisconsin, have invented certain new and useful Improvements in Igniters; and I do hereby declare that the following is a full, clear, and exact description thereof.

The primary object of my invention is to provide a simple, effective and economically constructed igniter for a group of gas burners.

A specific object of my invention is to provide means for intermittently supplying gas to a vented gas reservoir coincident to supplying an auxiliary charge of gas to a constantly burning pilot light under the reservoir, whereby said pilot light is flared to ignite the gas escaping from the firing vents of the gas reservoir.

Still another object of my invention is to provide the vented gas reservoir with a conical bottom plug, against which the torch-flame is directed, whereby the said gas reservoir is maintained at a high temperature, while at the same time the conical plug serves as a deflector for spreading the torch-flame radially to effect perfect ignition of the gas escaping from the firing vents, it being obvious that the heated chamber or reservoir will serve to expand the gases therein to accelerate their discharge into fine jet-like flames.

Another object of my invention is to provide a manually controlled valve for supplying gas to the reservoir and simultaneously supplying an auxiliary flow of gas to the torch, which torch is also constantly supplied with gas through the valve casing from a header or main pipe.

With the above and other minor objects in view the invention consists in certain peculiarities of construction and combination of parts as hereinafter set forth with reference to the accompanying illustrations and subsequently claimed.

In the drawings Figure 1 represents an elevation of an igniter embodying the features of my invention, with parts broken away and parts in section to more clearly illustrate details of construction, and Fig. 2, a detailed sectional plan view of the torch-head, the section being indicated by line 2-2 of Fig. 1.

Referring by characters to the drawings, 1 represents a gas main having fitted there-

to a valve-casing 2, the same being provided with a duct 3 that leads to the bottom of a well 4, which well has threaded therein a plug-shell 5. The bottom of the shell 5 is conically faced to form a mouth for a gas cavity 6, which cavity is normally closed by a valve member 7, the tapered head of the same being adapted to engage the conical faced mouth. When the valve member is seated it also serves as a closure for a duct 8 that leads to an annular recess 8' formed in the face of the plug-shell 5. This annular recess 8' in turn communicates with a main supply duct 8'', which duct communicates with a torch-tube 9 having its end tapped into the valve-casing. The main supply duct 8'' is constantly fed with gas from a by-pass duct 10 that leads from the bottom of the well 4, the said by-pass duct being regulated by a valve member 10' in the form of a pointed set-screw, which set-screw is in threaded union with the valve-casing and is adapted to restrict or increase the constant flow of gas from the main 1 to the torch-tube 9. The plug-shell is also provided with a second annular recess 11 that is connected to the gas cavity 6 by ports 11'. The annular recess 11 also communicates with a channel 12 that is formed in the valve-casing, which channel, in turn, communicates with an end of a feed-pipe 13, the said pipe being in threaded union with the valve-casing and, as shown, also incases the torch-tube 9.

The valve member 7 has a stem 7' which extends through the bore of the plug-shell and into a bonnet portion 5' thereof, at the base of which bonnet portion the stem is fitted with a soft gasket 14, constituting a packing, whereby gas is confined within the shell cavity. The valve-stem terminates with a push-button 15 having a neck that is in telescopic engagement with the bonnet cavity and interposed between the button neck and gasket is a coiled spring 16, which coiled spring serves to hold the valve member in engagement with its conical seat, whereby gas is checked from flowing into the feed-pipe 13 and also into the torch-tube, except through the by-pass 10. As previously stated, the torch-tube is incased within the feed-pipe and its outer end passes through a gas reservoir 16' that is formed in a head 17, the reservoir of which head 17 communicates with and is secured to the outer end of the feed-pipe. The top por-

tion of the head is sealed by an overhanging cap 17' and the bottom portion of said head is closed by a conical metal plug 18, which plug constitutes a deflector. The circular walls of the head are provided with radially disposed firing vents 19, which vents correspond in number to the burners grouped about the igniter, the vents being so aligned as to cause a jet flame to be discharged upon each burner of the group when the valve mechanism is operated.

The torch-tube 9, after passing through the head, is bent downwardly and its end is upturned to form a torch-tip 9', which tip is centrally disposed with relation to the conical plug 18. The torch-tip is protected by an open ended shield 20, which shield is suspended from the burner head by arms 20' that are crimped or otherwise made fast to the plug 18. Thus currents of air are permitted to pass upwardly through the shield and are deflected outwardly from the upper end of said shield by the conical plug, whereby vertical stratas of air are maintained about the torch at all times and said torch is thereby guarded against transverse currents which would tend to extinguish the same.

From the foregoing description it is apparent that a constant pilot light is maintained under the gas reservoir and to ignite any one or all of the stove burners the operator depresses the button 15, whereby the valve member will recede from its seat and establish communication between the gas main and gas cavity 6 of the plug shell. The full flow of gas from the main will thus be admitted to the gas reservoir 16' and simultaneously an auxiliary supply of gas will be delivered to the torch-tip 9', whereby the

said torch is flared to envelop the firing vents of the gas reservoir, causing ignition of said gas, whereby a series of jet flames are emitted from the head directly upon all of the burners grouped about the igniter. 45 When pressure is removed from the button 15 the supply of gas to the reservoir 16' is immediately cut off and the constantly burning torch is reduced to a small flame.

I claim:

1. In an igniter for stove burners comprising a vented reservoir, a feed-pipe therefor, and a torch-tube having its tip disposed under the reservoir; the combination of means for supplying a constant flow of 55 gas to the torch-tube, and valve-controlled means for simultaneously supplying an increased flow of gas to said torch-tube and a full supply to the reservoir.

2. An igniter for stove burners comprising a vented reservoir, a feed-pipe therefor, a torch-tube having its tip juxtaposing the reservoir, a valve-casing having a channel in communication with the reservoir feed-pipe and a main supply duct in communication with the torch-tube, the main supply duct being provided with a by-pass duct, a valve for controlling the reservoir supply pipe channel and torch-tube, and means for supplying a constant flow of gas to the 70 by-pass duct when the valve is closed.

In testimony that I claim the foregoing I have hereunto set my hand at Milwaukee in the county of Milwaukee and State of Wisconsin in the presence of two witnesses. 75

KEY D. CAMP.
